UNITED STATES PATENT OFFICE.

LAWRENCE B. JONES, OF TULSA, OKLAHOMA.

GUN BARREL.

Application filed March 19, 1926. Serial No. 95,968.

This invention relates to improvements in guns, the general object of the invention being to provide means whereby a shot-gun barrel can be increased in length to increase the range of the gun.

This invention also consists in certain other features of construction and in the combination and arrangement of the several parts, to be hereinafter fully described, 10 illustrated in the accompanying drawings and specifically pointed out in the appended claim.

In describing my invention in detail, reference will be had to the accompanying 15 drawings wherein like characters denote like or corresponding parts throughout the several views, and in which:—

Figure 1 is an elevation of a gun showing my improvement thereon.

20 Figure 2 is an enlarged sectional view.

Figure 3 is a view of the end of the barrel of the gun.

Figure 4 is a sectional view through the extension which is to be threaded on to the 25 threaded part of the barrel.

Figure 5 is an elevation, with parts broken away, showing a double barrel gun supplied with the improvement.

Figure 6 is a plan view of Figure 5.

30 Figure 7 is a view of the muzzle end of the gun shown in Figures 5 and 6, with the extension removed.

Figure 8 is a view of the extension shown in Figures 5 and 6.

35 Figure 9 is a detail view of a double barrel shotgun with but one barrel provided with the extension.

Figure 10 is a view of the muzzle end of said gun, with the extension removed.

40 Figure 11 is a view of the rear end of the extension shown in Figure 9.

In Figures 1, 2, 3 and 4, the barrel 1 of the gun is provided with an externally threaded muzzle part 2 which begins at an

45 annular enlargement 3 of the barrel, the rear part of the enlargement being beveled, while its front face is straight. This enlargement carries the sight 4. The extension for making the gun a long range gun 50 is shown at 5 and the rear part of the bore of said extension is enlarged and of cylindrical shape and provided with the threads 6 so that it can receive the threaded part 2 and when the extension is screwed home on

55 the barrel, its rear end, which is slightly

enlarged as shown at 7, will abut the front face of the enlargement 3, while the front end of the part 2 of the barrel will abut a shoulder 8 formed at the junction of the threaded part 6 of the bore, with the rest 60 of the bore. The major portion of the bore of the extension tapers from the part 6 to the muzzle end so as to provide a choke bore.

With this extension, a short range gun 65 can be changed into a long range one by simply screwing the extension on to the barrel of the gun. Thus it is not necessary to have a number of barrels for converting a short range gun into a long range one 70 or vice versa. The extension can be easily carried on the person, as it will be of light weight.

Figures 5, 6, 7 and 8 show an extension 5' for a double barrel gun 1'. In this case, 75 the double barrel extension 5' is provided with a pair of rearwardly extending rod-like projections 9 for engaging holes 10 formed in the web 11 which is placed between the barrels of the gun. A cam lock 80 lever 12 is pivotally arranged on the lower part of the web and operates through a hole 13 for engaging the lower projection 9 to hold the extension in place. As will be seen from the drawings, the projections 9 extend 85 a considerable distance along the upper and lower parts of the double barrel extension and form ribs 9' so that the projections are firmly connected with the extension.

In this case, both barrels of the gun are 90 extended when the device is placed thereon.

Figures 9, 10 and 11 show a modification in which an extension 5'' having but a single barrel can be used, with either of the barrels of a double barrel shot-gun. The 95 shot-gun is provided with the openings 10 as before explained, and the extension 5'' has an enlargement 14 at one side thereof which carries the rod-like projections 9'' for engaging the holes 10. These parts are so 100 arranged that the extension can be placed in front of either barrel of the shot-gun, with the rods 9'' engaging the holes 10 so that either barrel of the shot-gun can be extended. Any suitable means can be used 105 for holding the extension on the gun.

It is thought from the foregoing description that the advantages and novel features of my invention will be readily apparent.

I desire it to be understood that I may 110

make changes in the construction and in the combination and arrangement of the several parts, provided that such changes fall within the scope of the appended claim.

5 What I claim is:—

In combination with a double barrel shotgun having holes in the muzzle end of the

web of the gun, an extension, projections on the extension for engaging the holes and means for fastening the projections in the holes.

In testimony whereof I affix my signature:

LAWRENCE B. JONES.
